his attorney.

UNITED STATES PATENT OFFICE.

CHARLES F. ROM, OF CINCINNATI, OHIO.

TRUNK-TRAY SUPPORT.

937,866.

Specification of Letters Patent. Patented Oct. 26, 1909.

Application filed April 30, 1909. Serial No. 493,187.

To all whom it may concern:

Be it known that I, CHARLES F. ROM, a citizen of the United States, residing at Cincinnati, in the county of Hamilton and State 5 of Ohio, have invented certain new and useful Improvements in Trunk-Tray Supports, of which the following is a specification.

It is the object of my invention to provide a new and useful trunk-tray support so constructed that the same will automatically spring into action for supporting the trunk-tray when the tray is raised, and so arranged as to prevent the unintentional release or accidental closing of the tray, and the invention 15 consists in the novel construction and arrangement of the parts.

The invention will be readily understood from the following description and claims, and from the drawing, in which latter:

20 Figure 1 represents a rear perspective view of so much of a trunk and its tray as is necessary to illustrate my invention, the same being partly broken away, with the tray in closed position. Fig. 2 is a similar 25 view illustrating my improved device with the tray in raised position. Fig. 3 is a horizontal section on the line $z-z$ of Fig. 1, showing the body and tray of a trunk partly broken away, with my improved device in 30 position, and the tray in closed relation. Fig. 4 is a vertical section on a line corresponding to the line $z-z$ of Fig. 3. Fig. 5 is a vertical section on a line corresponding to the line $y-y$ of Fig. 3; and Fig. 6 is a 35 rear perspective view of my improved device, shown attached to a tray which is broken away.

1 represents the body of the trunk and 2 represents the tray which is pivoted to the 40 body by means of hinges, one of which is shown at 3. These hinges may be releasable hinges so that the tray may be removed from the trunk if desired.

4 is an anchor-plate which is secured to the 45 corner of the tray and preferably comprises a rubbing-plate 5 from which a flange 6 extends at substantial right angles, forming a corner 7 which is coincident in position with the corner 8 of the tray. The anchor-plate 50 is secured to the tray in suitable manner, as by means of cleats 9 passing through the anchor-plate into the tray.

The anchor-plate is provided with a raised boss 10 struck up from the metal of which 55 the anchor-plate is composed and forming a channel 11 in which the head 12 of a rivet

13 slides, there being a slot 14 in said raised boss through which the shank of the rivet passes.

16 is a leaf-spring support comprising a 60 securing portion 17, which is secured to the side of the tray, as by means of cleats 18, an outwardly bent portion 19, and an inwardly extending lip 20, the latter riding upon the rubbing-plate portion of the anchor-plate 4. The edges of the movable portions of the leaf-spring support are bent inwardly as shown at 21 for presenting the edges of the support toward the tray and removing said edges from contact with the 65 body of the trunk, especially from contact with the lining 22 of the same. The leaf-spring support is preferably bent up from a piece of sheet metal, the inward bends of the edges of the same increasing in size to 70 toward the inwardly extending lip, these inward bends also being formed upon said inwardly extending lip and being also provided at the corner 24 of the leaf-spring support which is adjacent in position to the 75 corner 7 of the anchor-plate when said support is in closed relation. The rivet 13 is secured to said inwardly extending lip and passes through the slot 14, thereby forming 80 limiting means between said leaf-spring support and anchor-plate.

When the tray is brought into raised position the outer end of the leaf-spring support will automatically spring outwardly as soon as the tray has been swung upwardly 90 on its hinges sufficiently to raise the leaf-spring support above the upper edge of the side 25 of the body of the trunk, thereby bringing said leaf-spring support into vertical alinement with said side and preventing the tray from dropping back to lowered position until the movable part of the said leaf-spring support has been again pushed inwardly out of vertical range with said side, the inwardly bent edges of the movable 100 portion of said leaf-spring support preventing injury to the lining of said body, and the construction and arrangement insuring ease of movement, reliability in the performance of the functions of the device, and a 105 strong support for the tray.

My improved device also prevents accidental dropping of the cover 26 of the trunk, when the tray is in raised position, the cover being pivoted on hinges 27.

My improved construction forms a strong support for the tray when the latter is

raised, and also forms a spring-structure of great resilience so that the support will snap into place immediately upon the raising of the tray and prevent unintentional falling of the same, while at the same time it presents rounded edges to the body of the trunk for preventing injury to the lining thereof.

Having thus fully described my invention, what I claim as new and desire to secure by Letters Patent is:

1. In a trunk-tray support, the combination with the body of a trunk, a tray therefor, and means for pivotally supporting said tray upon said body, of an anchor-plate secured at the corner at said tray, said anchor-plate having a raised boss struck up therefrom for forming a channel under said anchor-plate, there being a slot in said raised boss, a leaf-spring secured to the side of said tray at a point distanced from said corner thereof and having an inwardly extending lip, a rivet secured to said inwardly extending lip, the head whereof has movement in said channel of said anchor-plate, the sides of said leaf-spring being curled for presenting the edge-faces thereof toward said tray and presenting rounded faces toward the body of said trunk, substantially as described.
2. In a trunk-tray support, the combination with the body of a trunk and a tray pivoted therein, of an anchor-plate comprising a plate and a flange struck up at right angles therefrom for forming a corner which mates the corner of said tray, said plate having a raised boss struck up therefrom which

is provided with a slot and which forms a channel thereunder between said anchor-plate and said tray, a leaf-spring support secured to the side of said tray at a point 40 distanced from the corner thereof and provided with an inwardly extending lip which rides upon said anchor-plate and forms a corner, a connection comprising a shank and a head and secured to said inwardly extending lip, the shank of said connection passing through said slot and the head thereof received in said channel, and the sides of said leaf-spring support being curled for presenting the edges thereof toward said tray and the rounded faces thereof toward the body of said trunk, and constructed and arranged for holding the corner of said leaf-spring support adjacent the corner of said anchor-plate when said tray is in lowered position, said leaf-spring support being arranged for having its corner automatically spring outwardly away from said tray when said tray is in raised position for forming a support for said tray, 60 and the walls of said slot and said connection for said inwardly extending lip forming limiting means for said movement of said corner of said leaf-spring support, substantially as described.

In testimony whereof, I have signed my name hereto in the presence of two subscribing witnesses.

CHARLES F. ROM.
